UNITED STATES PATENT OFFICE.

JAMES H. BOYE, OF CHICAGO, ILLINOIS, ASSIGNOR TO THE BOYE NEEDLE COMPANY, OF CHICAGO, ILLINOIS, A CORPORATION OF ILLINOIS.

COMBINATION THIMBLE AND NEEDLE-THREADER.

1,143,249.

Specification of Letters Patent. Patented June 15, 1915.

Application filed August 7, 1914. Serial No. 855,637.

To all whom it may concern:

Be it known that I, JAMES H. BOYE, a citizen of the United States, residing at Chicago, in the county of Cook and State of Illinois, have invented a new and useful Improvement in Combination Thimbles and Needle-Threaders, of which the following is a specification.

This invention relates particularly to a combined thimble and needle-threader; and the primary object is to provide a thimble with a needle-threader which is so constructed and combined with the thimble as to form an inconspicuous attachment, the threader being so guarded as to prevent danger of catching on any delicate fabric when the thimble is used in the ordinary way in the operation of sewing.

The invention is illustrated in its preferred embodiment in the accompanying drawing, in which—

Figure 1 represents a greatly enlarged view of a combined thimble and needle-threader embodying my invention; Fig. 2, a similar view, in which a needle is shown broken and partly in section in the threading operation; Fig. 3, a similar view showing the final operation of threading the needle; Fig. 4, a section taken as indicated at line 4 of Fig. 1; Fig. 5, a similar section, showing the threader-hook engaged by the needle (shown in section), and thus bent away from the thimble; and Fig. 6, a broken section as indicated at line 6 of Fig. 1.

In the construction illustrated, A represents a thimble; and B a needle-threader combined therewith.

The thimble is provided at its large, or open, end with a bead 1 which is formed by curving the metal outwardly and downwardly, or toward the closed end of the thimble, as most clearly shown in Fig. 6. The threader B comprises a very thin member which is disposed just beneath the bead 1 and extends parallel therewith, the member being curved to conform to the curvature of the thimble so that the member will hug closely the outer wall of the thimble. The member is formed, or stamped, from a thin strip of steel, and is preferably suitably tempered. It has a shank 2 provided at its base with an edgewise extension 3 which is firmly clenched between the lower edge of the bead 1 and the adjacent wall of the thimble. At the free extremity of the mem-

ber is a hook having an upturned barb 4, the extremity of the hook projecting over a recess, or depression, 5 formed by striking the metal of the thimble inward just below the bead 1. The threader is provided at an intermediate point with a downwardly-extending lug 6 which affords a stop which serves to prevent the needle from being passed far enough toward the base of the threader to permanently bend the threader outwardly away from the thimble.

The thimble is provided with circumferentially-extending outwardly-struck embossments 7 and 8 which are disposed just below the threader and are separated by a space 9 which accommodates the lug 6 of the threader. The thimble is also provided with an outwardly-struck vertical embossment 10 which is disposed some distance from the point of the hook and borders the depression 5. That is, the embossment 10 extends at right angles to the bead 1 and is disposed immediately below said bead. It thus affords a guide for the needle 11.

In the operation of threading the needle, the needle is passed along the member 10 until the head of the needle engages the lower side of the bead 1, and is then moved parallel to itself until the hook of the threader passes through the eye of the needle in the manner shown in Fig. 2. The thread 12 is then, by an easy and natural movement, looped over the barb of the hook, and afterward the needle is moved off the hook, completing the threading operation. It will be understood that the lower edge of the bead 1 forms a guide for the head of the needle while the needle is being moved laterally to engage the hook of the threader. The engagement of the hook with the eye of the needle is easily effected by reason of the fact that the extremity of the hook projects over the depression 5. The threader, as a whole, however, closely embraces the outer wall of the thimble, and is suitably guarded, or housed, by the members 1 and 10 which afford guides, and the embossments 7 and 8 disposed adjacent the lower edge of the threader.

For convenience of illustration, the thimble, and other parts, are shown of greatly exaggerated size, but it will be understood that, in practice, the threader may be made of very thin material and of small size, so that the guard parts need not be large. In

fact, the attachment is, in practice, so inconspicuous as to be hardly noticeable, and the threader is so well guarded in every direction as to obviate danger of injury either to the fingers or to any delicate fabric.

The foregoing detailed description has been given for clearness and understanding only, and no unnecessary limitation should be understood therefrom.

10. What I regard as new and desire to secure by Letters Patent is:—

1. The combination of a thimble having its open end provided with an external bead adapted to serve as a guide for the head of a needle, a projecting external guide-lug extending substantially at right angles to the bead, and a circumferentially extending needle-threader having a shank secured at its base-end to the thimble adjacent to said bead and having a hook with its extremity spaced a short distance from said guide-lug.

2. The combination of a thimble having its open end provided with an external bead adapted to serve as a guide for the head of a needle, a projecting external guide-lug extending substantially at right angles to the bead, a circumferentially extending needle-threader having a shank secured at its base-end to the thimble adjacent to said bead and having a hook with its extremity spaced a short distance from said guide-lug, and a guard-lug disposed beneath said thimble.

3. The combination of a thimble having its open end provided with an external bead, a projecting external guide-lug extending substantially at right angles to said bead, the thimble having a depression adjacent to said guide-lug, and a thimble disposed immediately below said bead and having a shank securely attached to the thimble and an extremity extending over said depression.

4. The combination of a thimble having its open end provided with an external bead, a projecting external guide-lug extending substantially at right angles to said bead, the thimble having a depression adjacent to said guide-lug, a thimble disposed immediately below said bead and having a shank securely attached to the thimble and an extremity extending over said depression, and a projecting external guard-lug on the thimble disposed below said thimble.

5. The combination of a thimble having its upper edge-portion curved outwardly

and downwardly and affording a bead, a circumferentially extending needle-threader disposed beneath said bead and so spaced with relation thereto that said bead will serve as a guide for the head of the needle and as a guard for the thimble, and projecting external guards on the thimble protecting the extremity and lower edge of the thimble.

6. The combination of a thimble having an outwardly and downwardly curved upper edge affording a bead, a circumferentially extending needle-threader having a shank with its base-portion secured by said bead, a projecting external guide-lug extending substantially at right angles to said bead and spaced a short distance from the extremity of the thimble, and a projecting external guard-lug disposed beneath the lower edge of the thimble.

7. The combination with a thimble having an outwardly and downwardly-turned bead at its open end, of a thimble comprising a member having a shank with its base-portion secured by said bead and having a hook at the opposite extremity, said thimble having an intermediate stop for the needle and said thimble having an outwardly-struck embossment extending at right angles to said bead and disposed a short distance from the extremity of the thimble, and having also an outwardly-struck embossment for the lower edge beneath the thimble.

8. The combination with a thimble provided at its open end with an external bead and having its wall struck inwardly to afford a depression adjacent said bead, of a needle-threader hook extending circumferentially of the thimble and curved to lie against the outer surface of the thimble, immediately below said bead, the extremity of said hook projecting over said depression.

9. The combination with a thimble provided with a depression, of a needle-threader hook extending circumferentially of the thimble and curved to lie against the outer surface of the thimble, the extremity of said hook projecting over said depression, and elevations on the outer surface of said thimble guarding said thimble-hook.

JAMES H. BOYE.
